Attorney

Patented Oct. 7, 1924.

UNITED STATES PATENT OFFICE.

ERWIN H. MANDLER, OF CHICAGO, ILLINOIS.

PARING ATTACHMENT FOR KNIVES.

Application filed February 23, 1923. Serial No. 620,806.

To all whom it may concern:

Be it known that I, ERWIN H. MANDLER, a citizen of the United States, residing at Chicago, in the county of Cook and State of Illinois, have invented new and useful Improvements in Paring Attachments for Knives, of which the following is a specification.

My invention relates to improvements in paring attachments for knives, and has for its primary object the provision of a novel and improved gage or guide attachment which is capable of application to paring knives of various sized blades and which will be securely held in a predetermined position.

Another important object of the invention is to provide a paring gage whereby the rind or skin of fruits and vegetables may be economically and expeditiously removed without cutting in any deeper than is absolutely necessary to remove the rind, thus saving a large percentage of the fruit or vegetable which would otherwise be pared off with the rind and thereby lost.

A still further object of the invention is to furnish a device of the character set forth which is very simple in construction and which may be cheaply manufactured.

With the above and other objects in view as will become more apparent as the description proceeds, the invention comprises certain novel features of construction and arrangement of the various parts as will be hereinafter described and claimed, and in order that the same may be better understood, reference is had to the accompanying drawing forming a part of this specification.

In the drawing,

Figure 1 is a side elevation showing the application of my invention to a paring knife;

Fig. 2 is a similar view of the other side of the knife;

Fig. 3 is a section on the line 3—3 of Fig. 1, and

Fig. 4 is a perspective view of the gage removed.

Referring specifically to the drawing wherein like reference characters designate like parts throughout the several views, numeral 5 denotes the blade of a paring knife of the usual type having a cutting edge 6.

My improved gage attachment is denoted generally by the numeral 7, being prefer-

ably stamped from sheet metal, the stock of which is formed adjacent either end with transverse rearwardly offset straps 8 between which and the body of the attachment 60 the knife blade passes, as best shown in Fig. 2.

Upon an inspection of Fig. 3 it will be noted that the paring gage is provided with a longitudinal recess which terminates at 65 the inner edges of the straps 8, and also that the stock 10 of the gage running longitudinally adjacent the cutting edge 6 is spaced from the blade 5 to permit passage 70 of the parings therebetween and out through the longitudinal recess. The upper portion of the recess is provided with a resilient keeper flap 9 having a plurality of transversely arranged rearward protuberances 11 which are adapted to engage 75 with the upper edge of the knife blade and maintain the cutting edge in a predetermined position, thus preventing a relatively narrow blade from slipping upwardly in 80 the gage. However, should it be desired to 85 take a very thin paring, the keeper flap 9 may be lifted up with the finger to permit the blade 5 to slide a short distance upwardly toward the top of the gage, the taking of a thin paring being thus made possible as will hereinafter appear. It will be 85 obvious that blades of varying sizes may be used, in view of the holding action of the keeper flap 9.

The top and bottom longitudinal edges of 90 the gage 7 are formed with outward lips 13 and 12 respectively, the bottom lip 12 serving as a bearing surface against the fruit or vegetable being pared, while the top presents a smooth surface for the forefinger 95 of the parer preventing the upper edge of the knife blade from digging thereinto, and adapting the device to double edged knives. Referring again to Fig. 3 and assuming, as 100 in practice is the case, that the rounded portion of the lower lip 12 is the bearing portion which engages the fruit, it will be immediately evident that the withdrawing of the cutting edge 6 therefrom will decrease the angle of the cut, thus diminishing the 105 thickness of the paring removed.

While I have described and illustrated the preferred embodiment of my invention in accordance with the patent statutes, yet it will be understood that I do not propose 110 to limit myself strictly thereto, since various changes and modifications will imme-

diately suggest themselves to those skilled in the art without departing from the spirit of my invention as defined by the following claims:

- 5 1. I claim:
  1. A paring attachment for knives comprising a metal body having a longitudinal opening intermediate its ends one longitudinal wall of said opening being offset from the plane of the other, integral keeper straps formed in said body portion and beneath which a knife blade is insertible, the cutting edge of said blade being adjacent said offset wall and spaced therefrom, the longitudinal edge of said attachment adjacent said cutting edge of said knife blade being formed with an out-turned guide lip, an integral flap extending into said opening from one longitudinal edge thereof, and said flap having a series of protuberances upon one face thereof selectively engageable
- 10 15 20

with the lock edge of a knife blade for limiting movement thereof transversely of said opening.

2. A paring attachment for knives comprising a metal body having a longitudinal opening intermediate its ends one longitudinal wall of said opening being offset from the plane of the other, integral keeper straps formed in said body portion and beneath which a knife blade is insertible, the cutting edge of said blade being adjacent said offset wall and spaced therefrom, the longitudinal edge of said attachment adjacent the cutting edge of said knife blade being formed with an out-turned guide lip, and resilient means carried by the upper longitudinal portion of said attachment engageable with the upper edge of said blade.

In testimony whereof I affix my signature.

ERWIN H. MANDLER.
